UNITED STATES PATENT OFFICE

ALBERT WOODALL SMITH, OF LAKESIDE, OHIO

DISHWASHER

Application filed May 14, 1927. Serial No. 191,438.

This invention relates to improvements in scouring and cleaning apparatus, and more particularly to such as are especially adapted for the cleansing of dishes and like articles.

5 Among the objects in view, is the effective and relatively rapid cleansing of dishes and like articles, by means of comparatively simple and inexpensive construction.

A further object is the direction of cleansing streams against the objects to be cleaned in spiral paths or paths covering adjacent areas, with a minimum amount of lapping of such paths.

With these and further objects in view, as 15 will in part hereinafter be stated, and in part become apparent, the invention comprises certain novel constructions, combinations and arrangements of parts as subsequently specified and claimed.

20 In the accompanying drawings:—

Figure 1 is a longitudinal vertical central section through a structure embodying features of the present invention, parts being seen in elevation.

25 Figure 2 is a side elevation thereof with parts broken away for disclosing interior structure.

Figure 3 is an inverted plan.

Figures 4 and 5 are enlarged detailed 30 views, in sectional elevation and sectional plan respectively, of the detachable connection for the rotary tray with the actuating shaft, Figure 4 being taken on line 4—4 of Figure 1.

35 Figures 6 and 7 are graphic projections indicating the path of a given jet, the path during the first revolution being seen in Figure 6, and during the first and second revolutions in Figure 7, a fragment only of the path being shown.

40 Referring to the drawings by numerals, 1 indicates a tank or housing supported on appropriate legs or other suitable framing 2, mounted on casters 3—3 to facilitate bodily 45 positioning of the complete machine. A sleeve 4 extends through and is fixed to the bottom of the housing 1 as by a rivet flange 5. Threaded into the upper end of the sleeve 4 is a tubular standard 6 which upstands centrally of and within the housing 1. The

sleeve 4 is formed with an annular shoulder 7 on which rests the bottom of a foraminous receptacle 8 arranged to surround the portion of sleeve 4 extending beyond the shoulder 7. A nut 9 is threaded on to said extended portion or sleeve 4 to clamp the bottom of the receptacle 8 against the shoulder 7 so that the tubular standard 6, screen or foraminous receptacle 8, sleeve 4 and body 1 are rigidly connected against relative movement in respect to each other.

Extending throughout the length and within the standard 6 and also throughout the length of the sleeve 4 and beyond the sleeve downwardly and beyond the standard 6 upwardly is a driving shaft 10, the lower portion below the sleeve 4 fixedly carrying a gear wheel 11 meshing with a pinion 12 driven by an electric motor 13 or other appropriate power means. Bearing sleeves 14—14 are arranged for the shaft 10, between the shaft and the sleeve 4 and between the shaft and the standard 6 for retaining the parts in their proper relative relation and allowing free rotation of the shaft 10. The upper end portion of the shaft 10 extending beyond the standard 6 is provided with a cross pin 15 and an annulus 17 surrounds the said upper end and is loosely fitted thereon and is notched at 18—18 to accommodate the outstanding end portions of the pin 15 and to cause the pin to deliver torsional stress to the annulus 17 to rotate the same during operation. Fixed to or formed integral with the annulus 17 is a sleeve 19 which extends downwardly from the annulus to a point just above the strainer or foraminous receptacle 8. A supporting plate 20, preferably in the form of a disc is arranged just above the strainer 8 and centrally apertured to accommodate the extension of the sleeve 19 therethrough. The disc or plate 20 is preferably formed with an internally threaded upstanding axial annular boss 21 threaded onto the lower portion of the sleeve 19 so as to cause the plate 20 to rotate with the sleeve when the sleeve is driven by rotation of the shaft 10. The housing 1 is cylindrical and a cylindrical open work wire basket indicated at 25 is

40 adapted to be arranged just inside the hous- 45 50 55 60 65 70 75 80 85 90 95 100

ing as a retainer for the dishes or like articles sustained by the plate 20. Said plate 20 is provided with an upstanding annular marginal flange 22 and the wire basket may be constructed to fit just within the flange to rotate with the plate 20 and its actuating parts.

A brush 23 is connected to, and carried by the under portion of the plate 20 and arranged with its bristles contacting the inward surface of the upstanding annular wall of the screening receptacle 8, so as to continuously sweep the same and prevent clogging by accumulation of solids. Beneath the screen 8, and between the same and the bottom of the housing 1 is a space 24 constituting a sump for the collection of the detergent fluid which gravitates thereto from the dishes upon which it is sprayed.

Outstanding laterally from and extending longitudinally of the housing 1 is a channel casing 26 communicating laterally directly with the housing 1. Extending longitudinally within the casing 26 is a detergent supply pipe 27 provided with a number of pivotally connected discharge nozzles 28. Each discharge nozzle 28 is pivoted to swing vertically and all of said nozzles are pivotally connected by a link 29, the lower end of the link 29 being connected by a pin and slot connection at 30^a with a short arm 30^b of a bell crank lever 30. The bell crank lever is pivoted at 31 to a bracket either fixed directly to the housing 1 or to a part of the sleeve 4. A link 32 pivotally engages the long arm of the lever 30 at one end, and at its opposite end is swiveled to a wrist pin outstanding from the gear wheel 33. The gear wheel 33 is rotatively carried by a bracket 33^a extending from the flange of sleeve 4. The gear 33 meshes with a pinion 35 carried by and fixed to the shaft 10 so that as the shaft is rotated by a motor 13, the bell crank 30 will be rocked or oscillated, and the link 29 will be reciprocated longitudinally, vertically. It will be observed that the gearing from motor 13 to shaft 10 is a substantial step downward, that is to say, the speed is very substantially reduced in the rotation of the shaft 10 compared with the rotation of the armature of motor 13. Pinion 35 and gear 36 are ratioed to further step down the speed of movement so that the reciprocations of the link 29 are comparatively very slow.

It is to be noted that while the gear 33 rotates about a vertical axis and therefore moves in horizontal planes, the link 32 delivers motion from the gear to the bell crank lever 30 which bell crank lever is mounted to swing vertically and the direction of movement is therefore changed so that the link 29 is reciprocated vertically.

The gearing ratio between the gears 35 and 33 is such as to cause both a slow movement of the nozzles 28, and such a movement

relative to the speed of rotation of the plates 20 and parts carried thereby, that the streams played upon said carried parts from the nozzles 28 are delivered not only in a gyrating or elliptical or otherwise shaped path, but such a path that the strokes of a stream of any given nozzle will lap or pass over the same area to a minimum extent only. This is very desirable in presenting new surfaces and areas to be cleansed with each revolution of the plate 20 and parts carried thereby.

A circulating pump 34 is connected to be actuated by a motor 13 and has an in-take pipe 35 communicating with the sump 24 and a discharge pipe 36 communicating with a lower in-take end of the pipe 27. A reliable source of detergent material under pressure is thus assured.

In operation, the dishes to be cleansed are placed on the disc or plate 20 and under certain conditions, that may be said to be usual conditions, the openwork or wire mesh basket 25 may be employed for retaining the dishes or other articles to be cleansed in proper position during the operation. The motor 13 is then turned on and as the pile or stack of dishes begins to rotate, the action of the pump assures a delivery of as many streams onto the dishes as there are nozzles 28. The relatively slow playing of the nozzles 28 up and down against a slowly rotating object causes the path of impact to vary constantly. Thus the movement of the nozzles causes the delivery of streams of water in different or constantly varying planes, whereas rotation of the stack of dishes causes the peripheral area of such dishes to be presented toward the on-coming sprays and such presentation continues to advance in paths at right angles to the path of the streams from the jets so that the vertical swinging or oscillatory movements of the jets causes the delivered streams to contact with the dishes in paths of sinusoidal form, as indicated in Figures 6 and 7. The ratio of the gears which drive the shaft 10 to the ratio of the gears which oscillate the nozzles 28 is such that the paths of impact from given nozzles lap only to a minimum extent as illustrated in Fig. 7 during the course of rotation of the stack of dishes, but there is a lag of one in respect to the other such that after a circle has been completed by a given jet about a stack of dishes, the jet starts the second circle slightly angularly retarded or advanced with respect to the beginning of the former circle, and therefore if the sinusoidal line described by the points of impact, as indicated at 40 in Figures 6 and 7, incident to the rotation of the stack of dishes and the oscillation of the particular jet is looked upon as made up of a series of hills and valleys, the second circle 41 being described about the stack of dishes will have its hills and valleys off-set slightly relative to those of the first, and so on, as indicated in Figure 7, until

every point in the whole area has been covered by the sweep of a given nozzle and engaged by the spray. As indicated in Figures 6 and 7, the neutral line 42 would represent the path, if the particular nozzle were held stationary and it will be understood that the degree of angular advance or retardation of one path relative to the next in successive rotations of the stack of dishes will be only such as will be fully covered by the spray of the jet so that while the paths themselves are not directly overlaid one with respect to the other, the margins of the sprays will lap and thus cover the entire area of surfaces of the stack of dishes in the course of successive revolutions.

It is to be observed that the bell crank lever 30 instead of being that of the ordinary type with both arms in the same vertical plane, has its short arm 30^b spaced from the long arm so that while the long arm extends at the outside of the casing 26, the short arm is arranged within the casing to engage and actuate the link 29 as above described. Said arms of bell crank lever 30 are connected by a rock shaft 31 which in effect, forms part of the bell crank lever. Said rock shaft 31 is journaled in a bearing 30^c extending through the wall of the casing 26. A packing gland 30 may be utilized (not shown), if desired about the shaft 30^c, but since the cleansing fluid descending on and about the dishes will find its way chiefly down through the screen 8 and into the sump 24, there is no substantial danger of leakage along the shaft 31, even without the precaution of the packing gland.

The housing 1 is preferably provided with any appropriate removable cover 36 which is preferably employed while the machine is in operation, but may be readily removed for access to the contents of the housing 1, or for changing the housing.

A preferred method of procedure involves the removal of the cover 36 and the lifting of the sleeve 19 vertically out of the housing 1 with the parts. The basket 25 will preferably be made in two or more sections that may constitute compartments for holding the dishes. Two of the compartments may be used for dishes proper and one of them for cups or any similar special forms of dishes, though all of this is not material to the invention. The basket compartments or sections for the dishes will be provided with inclined partitions so that the dishes may rest in inclined positions when they are disposed ready for cleansing. When the cover 36 is removed the sleeve 19 may be raised with the parts connected thereto, including the plate 20, reticule or basket 25 and annulus 17.

The standard 6 serves as a guide for the sleeve 19, and therefore for the balance of the parts, and when the annulus 17 comes to rest on the upper end of the standard 6 with the notches 18 surrounding the projecting

ends of the pin 15, the machine will be in condition for operation. The operator merely turns on the current for the motor 13 and the cleansing operation proceeds as above indicated. Any preferred liquid detergent may be utilized, and of course, the dishes may be rinsed by a similar operation if desired, but such rinsing of course, would involve the removal of the detergent contents of the housing 1, and the supplying of rinsing water.

An appropriately valved discharge opening indicated at 39 may be provided for the sump 24 to facilitate change of liquid contents of the apparatus.

An important feature of the present invention is the ease and facility of removal and replacement of charges or stacks of dishes or like articles to be cleansed, and incident to such arrangement, facility for access to and cleansing of the parts through the machine itself is of importance.

Having thus described my invention, what I claim as new and desire to secure by Letters Patent of the United States, is:—

1. In cleansing apparatus, the combination, with a rotary support, of means for jetting cleansing fluid toward an object on the support at an angle to the axis of rotation of said support, and means operated in timed relation with the rotation of the support for oscillating the jet.

2. In cleansing apparatus, the combination, with a substantially annular housing, of a power shaft extending substantially axially of said housing, a disc removably arranged within the housing and detachably connected to receive power from the shaft, said disc being adapted to sustain a stack of articles to be cleansed, means for directing cleansing fluid laterally against such stack, a strainer beneath said disc, means for delivering fluid passing said strainer to said cleansing fluid directing means, and means carried by the disc for cleansing said strainer.

3. In cleansing apparatus, the combination, of a support for articles to be cleansed, means for rotating said support, and means for circulating cleansing fluid past and in contact with articles carried by said support including laterally disposed nozzles, and means actuated from the power source for oscillating said nozzles.

4. In cleansing apparatus, the combination, with a housing, of a rotary support therein for sustaining articles to be cleansed, a cleansing fluid supply pipe arranged laterally of articles so supported, nozzles pivotally communicating with the said supply pipe and directed toward such articles to be cleansed and power means arranged beneath said housing, and connected to rotate said support and to oscillate said nozzles.

5. In cleansing apparatus, the combination, with a housing, a support therein for articles to be cleansed, pivotally mounted nozzles ar-

- ranged within the housing and disposed for directing cleansing fluid laterally against articles sustained by said support, a bell crank lever arranged with one of its arms within the housing and one of its arms outside the housing, means connecting the inner arm to oscillate said nozzles, and means exteriorly of the housing for oscillating the outer arm of said bell crank lever.
- 5 6. In an article cleansing apparatus, rotatable supporting means for the articles, jet directing means oscillatingly mounted at one side of the support, means for rotating the article supporting means, and means for oscillating the jet directing means in a plane other than one perpendicular to the supporting means axis, said rotating means and oscillating means having a common drive, said drive including gearing whose ratio is other
- 10 20 than an integer such that each succeeding path of the jet on the articles to be cleansed will bear an angularly spaced relation to the preceding path in each rotation of the supporting means.

25 In testimony whereof I affix my signature.
ALBERT WOODALL SMITH.
